UNITED STATES PATENT OFFICE.

EDWARD T. ROBINSON, OF ST. LOUIS, MISSOURI, ASSIGNOR TO ST. LOUIS CAR COMPANY, OF ST. LOUIS, MISSOURI, A CORPORATION.

SLIDING-DOOR GUIDE.

SPECIFICATION forming part of Letters Patent No. 768,312, dated August 23, 1904.

Application filed December 5, 1903. Serial No. 183,992. (No model.)

To all whom it may concern:

Be it known that I, EDWARD T. ROBINSON, a citizen of the United States, residing in the city of St. Louis, in the State of Missouri, have invented certain new and useful Improvements in Sliding-Door Guides, of which the following is a full, clear, and exact description, reference being had to the accompanying drawings, forming part of this specification.

10 My invention relates to a guide for directing the travel of doors, the guide being more particularly applicable to the doors of street-cars, the object of the invention being to furnish a guide of a construction that will accurately direct the path of travel of the doors and one in connection with which no projections are necessary in connection with the threshold or tread plate beneath the door.

20 My invention consists in features of novelty hereinafter fully described, and pointed out in the claims.

Figure I is a top view of a pair of my guides and the tread-plate beneath them, fragments of the doors by which the guides are 25 carried being illustrated in section. Fig. II is a side elevation of the parts seen in Fig. I. Fig. III is a vertical section taken on line III-III, Fig. II. Fig. IV is an elevation of one of the door-guides, with the parts beneath it 30 shown in section, taken on line IV-IV, Fig. II.

1 designates the tread-plate of a street-car doorway, which, as seen in Figs. III and IV, is preferably formed with a vertical outer face 2 and a beveled inner face 3. This tread-plate 35 is preferably of metal.

A and B are mating sliding doors which are suspended in any usual manner above the tread-plate 1. One of these doors is grooved vertically at its edge, and the other door, B, has 40 a tongue C, that is adapted to enter the groove in the first-named door.

4 designates the main body of the guide, that is carried by the grooved door A and which is of U shape, having rearwardly-extending arms 5. In the face of the body 4 at the edge of the door A is a groove 6, corresponding to the vertical groove in said door.

7 is an outturned wing extending horizontally from the outer body-arm 5 and then

downwardly in the form of a lip 8, which extends in a line parallel with the vertical face of the tread-plate 1.

9 is a wear-block, preferably of rubber, fitted to the inside face of the lip 8 and adapted to ride in contact with the outer edge of the 55 tread-plate 1.

10 is a brace-rib connecting the outer body-arm 5 and the wing 7 to reinforce said wing.

11 is an inturned wing extending horizontally from the inner arm 5 of the guide-body 60 and carrying a downturned lip 12, which extends in a line parallel with the beveled inner edge 3 of the tread-plate 1.

13 is a wear-block fitted to the inner face of the downturned lip 12 and adapted to ride in 65 contact with the inner edge of the tread-plate during the movement of the guide thereover.

The inner body-arm 5 and the wing 11 are united by a reinforcing-rib 14.

4 designates the body of the guide carried 70 by the door B and having the arms 5' corresponding to the arms 5 of the guide-body 4. The guide-body 4' bears a tongue 6', that corresponds with the tongue C, carried by the door B, and which is designed to enter the 75 groove 6 in the guide-body 4 of the opposing guide on the door A. In other respects the guide carried by the door B is similar to the guide on the door A, which has been fully described, it having the wings 7' 11' united to 80 the body-arms by reinforcing-ribs 10' and 14' and the down-turned lips 8' and 12'. These lips also bear wear-blocks (not shown) similar to those 9 and 13 hereinbefore referred to.

It will be seen that my door-guide may be 85 either right or left hand and carried by either a single door or a pair of mating doors and will readily and efficiently direct the travel of the door or doors to which they are applied and cause even and uniform movement of the 90 doors without there being any presence of projections on the tread-plate, which are a frequent source of annoyance upon the tread-plates of street-car doors.

I claim as my invention—

1. In a guide for sliding doors, the combination with a tread-plate, of a body portion secured to the door, and having wings pro-

jecting outwardly from two sides of said body portion and having means for engagement with said tread-plate, substantially as set forth.

2. In a guide for sliding doors, the combination with a tread-plate, of a body portion fitted to the door, having wings projecting outwardly from two sides of said body portion, provided with lips projecting downwardly from said wings to engage said tread-plate, substantially as set forth.

3. In a guide for sliding doors, the combination with a tread-plate, of a U-shaped body portion fitted to the door, having wings projecting outwardly from said body portion, provided with lips projecting downwardly from said wings to engage said tread-plate, substantially as set forth.

4. In a guide for sliding doors, the combination with a tread-plate, of a U-shaped body

portion fitted to the door, having wings projecting outwardly from said body portion, provided with lips projecting downwardly from said wings to engage said tread-plate and reinforcing-ribs uniting said body portion and wings, substantially as set forth. 20

5. In a guide for sliding doors, the combination with a tread-plate, of a body portion fitted to the door, having wings projecting outwardly from said body portion, provided with lips projecting downwardly from said wings to engage said tread-plate, and wear-blocks carried by said lips, substantially as 25 set forth. 30

EDWARD T. ROBINSON.
